Specification for Design.

Patented Sept. 22, 1914.

Application filed August 12, 1914. Serial No. 856,501. Term of patent 7 years.

To all whom it may concern:

Be it known that we, GEORGE M. BEARDSLEE and IRA L. FRENCH, citizens of the United States, residing at Chicago, in the county of Cook and State of Illinois, have invented a new, original, and ornamental Design for Shades or Bowls for Lighting-Fixtures, of which the following is a specification, reference being had to the accompanying drawing, forming a part thereof.

In the drawing:—Figure 1 is a side elevation of our shade or bowl illustrating our new design; the shade being more especially intended as a ceiling bowl, and of the closed bottom type. Fig. 2 is a bottom plan view thereof.

We claim:—

The ornamental design for a shade or bowl for a lighting fixture as shown.

GEORGE M. BEARDSLEE.

IRA L. FRENCH.
